UNITED STATES PATENT OFFICE.

JOHN B. SIEREN, OF DEFIANCE, OHIO.

ACETYLENE-LANTERN AND SHADOWLESS BASE.

1,166,267.

Specification of Letters Patent. Patented Dec. 28, 1915.

Application filed April 6, 1915. Serial No. 19,424.

To all whom it may concern:

Be it known that I, JOHN B. SIEREN, a citizen of the United States, residing at Defiance, in the county of Defiance and State of Ohio, have invented a new and useful 5 Acetylene-Lantern and Shadowless Base, of which the following is a specification.

The especial object of my invention is to provide an improved form of lantern base 10 adapted to hold an inverted globe and which will not produce a shadow or obscure the ground directly beneath the lantern, as occurs with the ordinary lantern having a solid base.

15 It is also an object of my invention to provide for the easy insertion and withdrawal of the globe from my lantern base; and to provide a lantern base which may be constructed at relatively small expense.

20 It is also an object of my invention to combine my base with lighting means of the acetylene type, having mechanical lighting means.

I attain the objects of my invention by 25 the mechanism illustrated in the accompanying drawings, in which—

Figure 1 is a side elevation, with a portion of the globe broken away to show the burner; Fig. 2 is a plan section looking down 30 from line 2—2 of Fig. 1, with globe removed.

Like characters of reference indicate like parts throughout the several views.

Referring to the accompanying drawings, 35 I provide an annular base member 1 secured to which are a plurality of standards 2 supporting a globe-supporting ring 3, to which are secured a plurality of lamp-supporting standards 4 secured to a suitable acetylene 40 lamp 6, and supporting a disk 5 spaced below the lamp. Suspended from ring 3 by metal straps 8 is a globe-supporting ring 10, one of the straps being provided with a catch portion 9 adapted to releasably engage 45 ring 3, as shown in Fig. 1. The acetylene burner 7 is provided with a suitable mechanical lighting device 12, operated by a suitable wire 13, which may be extended to a point above the globe 11, to light the device 50 without removing the globe, by pulling the wire 13 and projecting sparks over the burner. Any suitable mechanical lighter may be utilized, and I do not claim this

element as my invention. To remove the globe, catch portion 9 is released from its engagement with ring 3, and the globe supporting ring 10 lowered in the manner indicated in dotted lines in Fig. 1. As disclosed in Figs. 2 and 1, ring 1 is of larger size than ring 3 and than the globe 11, so as to 55 permit of the removal of the globe through the base ring 1, as will be readily understood after noting the drawings. The globe 11 is of the inverted type, thus fully protecting the burner and throwing light in all directions, vertically as well as laterally, so that 60 no shadow interferes with the usefulness of the lantern.

What I claim is:

1. A shadowless lantern base comprising 70 an annular base member, standards attached thereto supporting a globe encircling ring, standards secured to the globe encircling ring supporting a lantern tank having a burner depending therefrom, an inverted 75 globe encircling the burner, and a globe-supporting ring releasably supported from one side of the globe encircling ring, and non-releasably supported from the opposite side, substantially as disclosed. 80

2. An acetylene lantern comprising an acetylene tank, a burner depending therefrom and having mechanical lighting means operable without removal of the globe member, a plurality of standards supporting the 85 tank and supporting a disk spaced below the tank, a globe encircling ring to which the standards are engaged, a base ring of greater diameter than the globe-encircling ring, standards supporting the globe encircling 90 ring from the base ring, an inverted globe insertible through the base ring, a globe-supporting ring to retain the globe in place, a strap connecting the globe-encircling ring with the globe-supporting ring, and an 95 oppositely disposed strap having a catch portion releasably engageable with the globe-supporting ring, whereby to provide a shadowless lantern base into which an inverted globe may be readily inserted and 100 removed.

JOHN B. SIEREN.
